UNITED STATES PATENT OFFICE.

HENRY A. W. WARD, OF LOWER HUTT, WELLINGTON, NEW ZEALAND.

BOTTLE HOLDER.

Application filed August 9, 1922. Serial No. 580,749.

To all whom it may concern:

Be it known that HENRY ALBERT WILLIAM WARD, a British subject, residing at Lower Hutt, in the Provincial District of Wellington, New Zealand, has invented certain new and useful Improvements in Bottle Holders, of which the following is a specification.

This invention has reference generally to improvements in that class of inventions known as bottles and jars and more particularly relates to combined milk bottle holder and closure.

It is the principal aim and object of the invention to provide a device of the above character which is designed for releasable and rigid engagement with a milk bottle to permit of the bottle being manipulated in the nature of a pitcher, so that the contents of the bottle may be readily dispensed as desired.

As an additional and equally important object the invention embraces the provisions of a device of the above character wherein there is combined with the handle, a closure in the form of a movable lid, the same being normally adapted to close the mouth of the bottle but actuatable by the thumb or one of the fingers of the person grasping the handle when it is desired to dispense the contents of the bottle.

More particularly the present invention consists in the provision of means carried with the handle piece for binding engagement with the neck of the bottle, said means including generally curved resilient arms having their inner ends pivotally associated with the handle and being of such a length as to automatically grip the neck of the bottle, improved means being provided on the handle for co-acting with the arms to facilitate retention of the arms on the neck of the bottle.

More specific objects of the invention reside in the provision of stopper engaging means on the lid for facilitating the removal of the usual disc like stopper of the bottle; the improved construction of the bottle, and the improved details of structure of the holder.

Among the other aims and objects of the present invention may be recited the provision of a device of the above character with a view to compactness and wherein the number of parts are few, the construction simple, the cost of production low and efficiency high.

Further objects, as well as the nature, characteristic features and scope of the invention will be more readily apparent from the following description taken in connection with the accompanying drawings and pointed out in the claims, forming a part of this specification.

The invention is clearly illustrated in the accompanying drawings, in which:

Figure 1 is a side elevational view showing the device applied to the bottle, the mouth of the latter being broken away to illustrate the construction thereof, and the engagement of the closure carried prong with the stopper.

Figure 2 is another side elevational view showing the device applied, but looking toward the edge of the handle.

Figure 3 is a horizontal sectional view taken on line 3—3 of Figure 1, of the holder per se.

Figure 4 is a transverse section on the line 4—4 of Figure 1.

Figure 5 is an enlarged transverse sectional detail on the line 5—5 of Figure 1, and

Figure 6 is a perspective detail of the closure.

Similar characters of reference are employed in all the above described views, to indicate corresponding parts.

Referring now, more particularly, to the accompanying drawings there is provided a bottle 1 of the type generally used for containing milk with a slight modification consisting of an elongated neck portion 2, the mouth of which is formed with a relatively small spout 3, while the interior of the neck is formed with an annular shoulder 4 at a suitable distance from the outer edge of the bottle for the reception of a disc like stopper 5 of a conventional type. Removably associated, yet rigidly connected with the bottle is the improved combined holder and closure indicated in its entirety by the numeral 6.

In reducing the invention to practice there is provided an annular bottle body encircling band or ring 7 which may be formed of strip metal, the ends being arranged in overlapped relation and secured together as by a suitable fastener 8. A handle 9 is now employed, the lower end being offset and secured to the ring 7 by suitable fastening means 10. The upper portion of the handle 9 is likewise offset as at 11 and terminates in

an upright bottle neck engaging portion 12 the extreme terminal of which is in the form of a lip 13 for reception within a groove 14' in the bottle neck.

5 Co-acting with this lip is the improved bottle neck engaging means in the present instance being in the form of curved resilient arms 14, the outer ends terminating in finger engaging portions 15 while the inner 10 ends are bent angularly to form the journaling portions 16, the latter being journalled within vertically disposed bearings 17 formed desirably integral with the side edges of an extension 18. As intimated these 15 arms are of such length and curvature as to automatically grip the bottle neck. This extension is secured by suitable fasteners to the outer face of the upright portion 12, the upper end terminating in a plane above the 20 upper edge of the body and serving as a means for supporting the improved closure.

In order to facilitate the extraction of the stopper 5 and to normally close the bottle there is employed an improved closure in the 25 form of a disc like lid 19 having a finger piece 20 projecting from a point on the periphery thereof, the latter in turn being provided near its point of junction with the lid with a transverse slot 21 for reception of the 30 extension 18. In this connection it is to be observed that the extreme upper end of the extension is bent outwardly to a slight extent while the finger piece is bent downwardly and by reason of the position of the 35 slot and the size thereof which is slightly greater than a cross section of the extension, pivotal movement of the lid 19 may be occasioned upon the depressing of the finger piece 20. Depending from the lid 20 is a headed 40 prong 22 which upon the application of the device upon the bottle is adapted to penetrate the disc like stopper 5 and upon the turning of the device, desirably before the 45 clamping of the arms 14, the head is anchored against the under surface of the stop-

per so that subsequent to the placing of the arms in binding engagement with the neck and simultaneously with the depressing of the finger piece 20 with the lid, the stopper will be removed from its position on the 50 shoulder. When removed, it being understood that the handle is in the grasp of the user, it is only necessary to tilt the device and manipulate the same in the nature of the usual pitcher for the dispensing of the 55 contents of the bottle as desired.

It is believed in view of the foregoing description that a further detailed description of the operation of the invention is entirely unnecessary. Likewise, it is believed that 60 the advantages of the invention will be readily apparent.

Having thus fully described the invention what is claimed as new and desired to be secured by Letters Patent is:—

65 1. A device of the character described including a bottle body embracing ring, a handle secured thereto, an extension connected with the handle and curved resilient bottle neck engaging arms pivotally mounted in 70 the extension and being of such a length and curvature as to automatically grip the bottle neck.

2. In a device of the character described in combination with a bottle having a body 75 and neck of a handle associated with the body, means in the handle for engaging the neck of the bottle, arms pivotally associated with the handle and being so constructed as to coact with the last mentioned means for 80 releasably clamping the handle to the neck.

3. A device as claimed in claim 2 wherein the bottle neck is provided with an abutment and the bottle neck engaging means including a lip on the handle for engagement with 85 the abutment.

In testimony whereof he affixes his signature.

HENRY A. W. WARD.
